FIG. 3.

UNITED STATES PATENT OFFICE.

THOMAS F. HERLIHY, OF BRIDGEPORT, CONNECTICUT, ASSIGNOR TO DICTAPHONE CORPORATION, OF BRIDGEPORT, CONNECTICUT, A CORPORATION OF NEW YORK.

RECORD-RESURFACING MACHINE.

Application filed June 4, 1927. Serial No. 196,490.

This invention relates to record-resurfacing machines, and more particularly to a locking mechanism for the mandrel supporting end-gate of such machines.

- 5 An object of this invention is to provide an end-gate locking mechanism which will automatically lock incidental to the movement of the end-gate to the mandrel supporting position.
- 10 Another object of this invention is to provide an end-gate locking mechanism, the release of which can be effected by movement of the end-gate out of the mandrel supporting position.
- 15 A still further object of this invention is to provide a self-acting end-gate locking mechanism which will yieldingly support the mandrel and will be self-compensating for wear.
- 20 In the accompanying drawings which illustrate one form of the invention, that at present preferred—

Figure 1 is a perspective view of a record-resurfacing machine showing the end-gate and the locking means therefor provided by the present invention in mandrel supporting position.

Fig. 2 is a fragmentary view of the end-gate and end-gate locking mechanism in closed or 30 mandrel supporting position.

Fig. 3 is a view similar to Fig. 2, the end-gate and end-gate locking mechanism being shown in the act of moving to the open position.

35 The kind of record-resurfacing machine selected for the purpose of illustrating this invention comprises a base 10 provided with a left-hand standard 11, a middle standard 12 and a right-hand standard 13. Supported 40 between the standards 11 and 13 is a guide rod 14 for supporting a carriage 15 whose forward end is provided with a shoe 16 adapted to ride on a rail 17 forming part of the frame 10.

45 The carriage 15 supports a record-cutter 18, movement of which with the carriage 15 over a record 19 for the purpose of resurfacing a record 19 is accomplished by the rotating feed-screw 20 in engagement with a 50 feed-nut 20^a mounted on the carriage 15. Rotation of the mandrel shaft 21 is accomplished by a motor or other suitable means (not shown) driving a pulley 22. Interconnected

rotation of the feed-screw 20 with the mandrel shaft 21 is accomplished by a belt 29. 55

The record blank 19 is supported for rotation on a mandrel 9 having a shaft 21 and a driving pulley 22. One end of the mandrel shaft 21 is supported by a conical center 23 in the left-hand standard 11, while the other 60 end is supported during rotation of the mandrel by a conical center 25 in an end-gate 26 which is pivotally mounted on a stud 27 on the standard 13 so that the end-gate may be opened to give access to the mandrel when 65 placing a record 19 on the mandrel 9 or removing one therefrom.

When the end-gate 26 is open, as shown in Fig. 3, the mandrel shaft 21 is retained in proper position by the cooperation of the 70 conical center 23 in the standard 11 and by the retaining standard 12. However, when the end-gate 26 is moved to the mandrel supporting position as shown in Fig. 2, the conical center 25 in the end-gate 26 lifts the 75 mandrel shaft 21 out of contact with the middle standard 12 which only loosely fits the shaft 21 and true rotation is then possible solely on the conical centers 23 and 25.

The above described structures and mechanisms are common to record-resurfacing machines heretofore manufactured and used, and form part of the present invention only in so far as they are related to or combined with the mechanism hereinafter described. 80

The present invention provides an improved locking mechanism for holding the mandrel end-gate 26 in mandrel supporting position and has the advantage of being self-acting and requiring no attention on the 90 part of the operator, for the functions are naturally and subconsciously performed. This is an extremely advantageous feature, since it replaces the locking mechanism heretofore provided which had to be separately 95 and manually operated, and hence required a mental effort on the part of the operator.

These advantages are obtained, according to the present invention, by providing a self-acting latch 30 mounted directly on the end-gate 26 adjacent the handle 26^a thereon and in position to engage a fixed keeper 31 or other cooperating latch member in the carriage guide rail 17 when the gate is closed. 100

As illustrated in the accompanying drawings, the latch 30 is mounted in a slot 32 in

the handle 26^a so as to be partially housed thereby and is adapted to pivot on a vertical pin 33. The latch 30 is normally urged toward its gate-locking position by a spring 34 mounted in the handle 26^a and bearing against part of the latch confined in the slot 32. Forward movement of the latch 30, when the end-gate 26 is not in locking position, is limited by a tongue 35 on the latch engaging a portion 36 of the end-gate 26, as shown in Fig. 3.

The fixed keeper 31 with which the latch 30 cooperates, is preferably removably mounted in the rail 17, and hence may be easily replaced in case of wear, and is provided with two cam surfaces 37 and 38, the purpose of which will hereinafter be described.

The function of the end-gate 26 is mainly to support the mandrel 23 for rotation to resurface the record 19. It is adapted to be swung on the stud 27 sufficiently in the direction indicated by the arrow in Fig. 3 to permit easy placement on and removal from the mandrel 9 of the record 19. When the record 19 is placed on the mandrel 9, the end-gate 26 is returned to mandrel-supporting position shown in Fig. 2, in which position the end-gate 26 abuts an end 28 of the rail 17, an aligning pin 50 on the gate entering an aperture 51 in the end 28 of the rail 17.

To close the lock the end-gate 26 in mandrel supporting position, the operator, according to the present invention, must merely push against the handle 26^a so as to cause it to move to the left as seen in Fig. 3.

As the end-gate 26 is moved toward the mandrel supporting position by the operator's fingers, as indicated in Fig. 2, the yielding latch 30 comes in contact with the fixed keeper 31. So that the latch will be self-acting, it has a cam surface 40 positioned to engage and ride over a cam surface 37 on the keeper 31. Thus, the latch 30 yields arcuately on the pin 33 against the pressure of the spring 34 until the point 41 on the latch rides over the point 42 on the keeper. As soon as these points pass, the latch 30 is forced to move clockwise, as seen in Fig. 2, under pressure of the spring 34 to engage the keeper beyond the point 42.

So that the end-gate 26 will always be held tightly in closed position with the gate close to the end 28 of the rail 17, even if the parts of the latch should become worn and to compensate for slight variations in the manufacture of the parts, the locking faces 38 and 43 of the latch 30 and keeper 31 respectively are not made plain, as is usual, but are made in the form of cams which are so inclined relatively that rotation of the latch 30 under the influence of the spring 34 causes the latch and its connected end-gate 26 to be drawn to the left as seen in Fig. 2. Since the end-gate 65 is resiliently held in closed position, it will be

seen that the conical center 25 will be yieldingly urged against the mandrel shaft end 24, thus accomplishing the double purpose of compensating for wear and eccentricities of the conical centers. 70

Upon completion of resurfacing the record 19, release of the end-gate locking mechanism, according to the present invention, can be easily accomplished incidental to the action of moving the end-gate 26 to the open position. As shown in Fig. 3, when the thumb or other finger is pressed against the finger-pad 44 of the yielding latch 30 when the end-gate 26 is in the mandrel supporting position shown in Fig. 2, the latch is swung out of locking position allowing the point 41 to ride over the keeper point 42. The further movement of the finger against the finger-pad 44 will quickly move the end-gate 26 to the open position. 80

As can be seen from the foregoing, the present invention provides a simple and efficient end-gate locking mechanism which is self-acting incident to the manual movement of the mandrel supporting end-gate 26. 90

Variations and modifications may be made within the scope of this invention and portions of the improvements may be used without others.

Having now described the invention, what is claimed as new and for which it is desired to obtain Letters Patent, is:—

1. In a record-resurfacing machine, the combination of a rotatable record mandrel; a movable end-gate to support the mandrel at one end for rotation; self-acting locking means for holding the end-gate in mandrel-supporting position, said locking means comprising two cooperating members; a spring acting to force said members together; one of said members having an oblique surface whereby said members may slide one upon the other and come to rest in holding position while the spring is still under compression, permitting said spring to urge said members into further holding positions to take up progressive wear of the parts. 100

2. In a record resurfacing machine, the combination of a rotatable record mandrel; a movable end-gate to support the mandrel at one end for rotation; a self-acting locking means for holding the end-gate in mandrel-supporting position, said locking means comprising a fixed keeper, a yielding latch and a latch spring, the latch being provided with an angularly disposed portion positioned for manual operation to move the latch away from the keeper in a path substantially at right angles to the initial opening movement of the end-gate. 115

Signed at Bridgeport, in the county of Fairfield, and State of Connecticut, this 1st day of June, 1927.

THOMAS F. HERLIHY.
